Attorney.

UNITED STATES PATENT OFFICE

2,354,832

ADJUSTABLE BRACKET AND BRUSH FOR
WINDOW SHADES

George Ristine, Philadelphia, Pa.

Substituted for abandoned application Serial No.
248,405, December 30, 1938. This application
June 13, 1944, Serial No. 540,074

6 Claims. (Cl. 160—11)

This is a substitute for my previous application 248,405, filed December 30, 1938.

My invention relates to new and useful adjustable brackets and brushes for window shades, and has for one of its objects to provide a casing that can be adjusted to different sized window shades to protect the same from dirt or dust and beautify the surroundings.

Another object of this invention is to provide a combination of adjustable window shade brackets, an adjustable ornamental casing detachably fastened to the brackets, and brushes carried by said brackets to cleanse the surfaces of a shade as the latter is rolled and unrolled.

Another object of the invention is to provide adjustable brackets to accommodate different sized shades and their rollers and including means to support brushes and other means whereby a casing may be attached to said brackets.

A further object of the invention is to provide an adjustable ornamental casing fashioned to fit the contour of the brackets to which it is to be attached whereby said brackets function as the back and ends of the casing and said casing adapted to enclose the rolled portions of the shade and its roller thereby adorning an otherwise prosaic article.

With the above and other objects in view, this invention consists of the details of construction and combination of elements hereinafter set forth and then designated by the claims.

In order that those skilled in the art to which this invention appertains may understand how to make and use the same, I will describe its construction in detail, referring by numerals to the accompanying drawing forming a part thereof, in which—

Fig. 1 is a perspective view of the complete apparatus as it appears when in use.

Fig. 2 is a transverse sectional view thereof.

Fig. 3 is a perspective view of the brackets in cooperative relation.

Fig. 4 is a broken bottom view of the complete apparatus.

In carrying out the invention as herein embodied 5 and 6 represent companion, cooperating bracket members slidably connected to one another for adjustment to fit or support window shades of different sizes.

The bracket member 5 comprises a back 7 having holes 8 therethrough and along each horizontal or longer edge is formed a roll flange 9 with a slot 10. An integral bracket 11 projects forwardly from the outer end of the back at right angles thereto and has a slot 12 for the reception

of the rectangular pindle of a window shade roller. The inner or closed end of the slot 12 is preferably located in an upset hub 13 pressed from the bracket material. On some suitable portion of the bracket 11, for instance, in the region of the front part of its periphery, is an inturned lug 14, formed with the bracket and bent over at right angles thereto. A threaded hole 15 is formed in said lug to receive a screw as will be presently described.

On the inner surface of the bracket 11 at or near the bottom thereof is a brush support 16 in the form of a channel with its back wall against the face of the bracket and its flanges projecting away from said bracket. The channel is in a horizontal position and its outer end is open. The flanges of this brush support have notches 17 therein intermediate their ends and said notches are in vertical alignment.

The bracket member 6 is similar to the other one and includes a back 18 having holes 19 therethrough and along each horizontal or longer edge is formed a roll flange 20 of a size to fit or telescope into the roll flange 9 of the bracket member 5 while the back 18 enters the slots 10 to allow one bracket member to be adjusted longitudinally relative to the other. An integral bracket 21 projects forwardly from the outer end of the back 18 at right angles thereto and has a hole 22 for the reception of the round pindle of a window shade roller and said hole is in the upset hub 23 pressed from the bracket material.

On some suitable portion of the bracket 21, for instance, in the region of the front part of its periphery, is an integral inturned lug 24 formed with the bracket and bent over at right angles thereto. A threaded hole 25 is provided in said lug to receive a screw to be hereinafter referred to.

On the inner surface of the bracket 21 at or near the bottom thereof is a brush support 26 which, like the one previously described, is of channel formation with its back against the face of the bracket and its flanges projecting away from said bracket. This channel is also in a horizontal position and its outer end is open. The flanges of the brush support 26 have notches 27 therein intermediate their ends and said notches are in vertical alignment.

A window shade roller 28 with the usual spring 29 is mounted in the brackets 11 and 21 and the shade 30 thereon has a depending portion that passes through the notches in the brush supports 16 and 26. This arrangement prevents the edges of the shade from being rubbed by the

flanges of the supports and frayed or otherwise damaged.

Two brushes 31 and 32 have their ends mounted in the brush supports 16 and 26, one on each side of the notches and extending across the space between the brackets with the bristles of each brush projecting towards the other so that the depending portion of the shade passes between the bristles of said brushes. The brushes engage opposite faces of the shade and dislodge any dust or other foreign matter that may have a tendency to accumulate thereon as the shade is rolled up or unrolled.

That portion of the shade which is on its roller is housed and protected by an ornamental casing 33 comprising two sections 34 and 35. These are fashioned to have the contour of the top and front edges of the brackets and also may be shaped to provide an apron 36 of approximately scroll shape in an end view.

One of the sections, as 34, has a roll flange 37 along each of the longer edges and is so formed as to provide a slot 38. The other section, as 35, also has a roll flange 39 along each of its longer edges but smaller than the flanges 37 so as to slide or telescope therein with portions of the casing section 35 passing into the slot 38 to permit the sections to be adjusted longitudinally to correspond to the adjustment of the bracket members.

The casing is assembled over the brackets to house the rolled part of the shade and brushes and therefore keeps out dirt, dust and the like so the brushes principally remove any substances that adhere to the depending portion of the shade as it is rolled up. This will eliminate, to a considerable extent, dust particles which often cause pin holes in the shade material when rolled therein. When the casing has been properly positioned, screws 40 and 41 are inserted in holes in the casing sections and screwed into the holes 15 and 25 in the lugs 14 and 24 respectively.

Any desirable portion or portions of the casing sections may be ornamented as at 42 to give a beautiful finish and appearance to the entire shade mounting and cleaning apparatus.

Of course I do not wish to be limited to the exact details of construction herein shown and described as these may be varied within the scope of the appended claims without departing from the spirit of my invention.

Having thus described my invention, what I claim as new and useful is:

1. In a device of the kind described, the combination of two bracket members adjustably connected and including outwardly projecting brackets to hold a shade roller and a shade thereon, brush supports on said brackets, and brushes on said supports to engage opposite faces of the depending portion of the shade.

2. In a device of the kind described, two coating bracket members each comprising a back with holes therein, outwardly projecting brackets to receive pintles of a shade roller, inturned lugs with threaded holes adapted to receive screws for attaching a casing to said lugs, channel brush supports on the inside lower portions of the brackets adapted to receive and support brushes, roll flanges with slots along the longer edges of the back of one bracket member, and roll flanges along the longer edges of the back of the other bracket member to telescope into the first mentioned roll flanges.

3. In combination, a pair of bracket members each comprising a back, interengaging roll flanges along the longer edges of said backs, brackets projecting from the outer ends of said backs and adapted to support a shade on a roller, inturned lugs on said brackets and provided with threaded holes and brush supports carried by the brackets and consisting of channels with their flanges projecting away from their respective brackets, the flanges of the supports having vertically aligned slots for the passage of the edges of a depending portion of a shade, and brushes in said supports, one on each side of the slots so that the bristles of the brushes engage opposite faces of the depending portion of the shade.

4. In a device of the kind described, bracket members including outwardly projecting brackets to hold a shade roller and a shade thereon, channel brush supports on said brackets in horizontal positions and having notches vertically arranged for the passage of the edges of the depending portion of the shade, and brushes in said supports to engage opposite faces of said depending portion of the shade.

5. In a device of the kind described, bracket members including outwardly projecting brackets, brush supports on the inner faces of the brackets and consisting of channels with their flanges projecting away from their respective brackets and the flanges of said supports having vertically aligned slots for the passage of the edges of a depending portion of a shade, and brushes in said supports, one on each side of the slots so that the bristles engage opposite faces of the depending portion of the shade.

6. In a device of the kind described, bracket members including outwardly projecting brackets having pintle receiving apertures to hold a shade roller with a shade thereon, horizontal channels on the inner surfaces of said brackets to the rear of the pintle receiving apertures, said channels having vertical notches for the passage of the edges of the depending portion of the shade, and opposed brushes in said channels to engage opposite faces of said depending portion of the shade.

GEORGE RISTINE.
